UNITED STATES PATENT OFFICE.

AUGUST TEGOLI, OF SANTA ROSA, CALIFORNIA, ASSIGNOR TO TEGOLI DRYING APPARATUS MANUFACTURING COMPANY, LTD., A CORPORATION OF CALIFORNIA.

DRYING-MACHINE FOR ALIMENTARY PASTES.

1,214,239.

Specification of Letters Patent. Patented Jan. 30, 1917.

Application filed May 24, 1916. Serial No. 99,619.

To all whom it may concern:

Be it known that I, AUGUST TEGOLI, a subject of the King of Italy, residing at Santa Rosa, in the county of Sonoma and State of California, have invented certain new and useful Improvements in Drying-Machines for Alimentary Pastes, of which the following is a specification, reference being had to the accompanying drawings.

10 This invention relates to improvements in drying machines and particularly machines for drying alimentary pastes used in the manufacture of macaroni, spaghetti, vermicelli, etc.

15 The general object of this invention is the provision of a drying machine in which the paste can be quickly and uniformly dried without causing the paste to crack in the drying process.

20 A further object of the invention is the provision of a machine of this character in which the fresh air entering the machine is uniformly distributed so that no one portion of the paste is subjected to a greater 25 action than another portion and further that fresh air entering the drying room may be thoroughly mixed with warm air which has been previously passed through the drying chamber.

30 Still another object of the invention is the provision of means whereby fresh air may be drawn through the drying room or compartment without intermixture with air previously drawn through the compartment or 35 drying room.

Still another object is to provide means whereby the relatively warm air may be carried directly downward into any one of a series of rack supporting trucks.

40 Other objects will appear in the course of the following specification.

My invention is illustrated in the accompanying drawings wherein, Figure 1 is a vertical sectional view of a drying machine 45 constructed in accordance with my invention; and Fig. 2 is a longitudinal sectional view thereof.

As will be seen by reference to these drawings, 10 designates a drying chamber or room which is relatively long and which is provided on one side with doors 11 which are preferably double doors by which a series of trucks 12 and 13 may be shifted into the drying room or chamber. Disposed at

one end of the drying room 10 is an exhaust 5 fan 14 disposed in an opening in a partition 15, this exhaust fan being mounted upon a shaft 16 driven in any suitable manner, said shaft being located in what I will call the circulating chamber 17. There is a 60 window 18 in the end of the circulating chamber 17. This window constitutes a more or less adjustable closure to regulate the passage of air from the circulating chamber 17.

The chamber 10 is disposed in a relatively large room or chamber 19 of which the circulating chamber 17 forms part. This chamber 19 extends at one end to form the circulating chamber above described and at the 70 other end to form the circulating chamber 20. The end wall of the circulating chamber 20 is formed with louvers 21, through which fresh air passes. The end wall of the chamber 10 adjacent the louvers 21 is 75 also formed with louvers 22. The chamber 19 extends above the top wall of the chamber 10 in the form of an air passage designated 23, which leads from the circulating chamber 17 to the circulating chamber 20 80 and at opposite ends this air passage 23 is provided with the controlling doors 24 and 25 which are so mounted that they may be independently shifted either into a vertical position preventing the circulation of air 85 along the passage 23 or disposed in a horizontal position, as illustrated in Fig. 1, permitting the circulation of air. Also disposed in the top wall of the chamber 10 are the flues 26, each formed with a hinged 90 cover 27, means being provided whereby these covers may be opened or closed.

The chamber 10 is designed to contain a plurality of trucks, certain of the trucks, as for instance the trucks 12, being arranged 95 to support what is known as long paste and, to this end being provided with a plurality of rods 28. Certain other trucks, as for instance the trucks 13 are formed with trays having bottoms of wire network, upon which 100 may be laid what is known as coil paste.

In practical use, the air is drawn into chamber 10 by means of the exhaust fan 14, air being drawn through the louvers 21 and 22, these louvers acting to thoroughly distribute the air so that no one portion of the paste which is to be dried, will be subjected to more air than any other portion. Under

normal circumstances, the exhaust fan 14 will draw the air in the direction of the arrows in Fig. 1 and then force the air up into the air trunk or passage 23, the air traveling 5 back along this passage and passing into the circulation chamber 20 where it mixes with the fresh air in the chamber 20 and passes through the louvers 22 and back into the chamber 10. If it be desired to draw entirely 10 fresh air through the chamber 10 and not intermix this fresh air with the air previously drawn through the chamber 10, then the door 24 is closed and if it be desired to cause the air to pass from the chamber 10 into the 15 passage 23 and then down through any of the flues 26, the door 25 is closed and one or more of the doors 27 are opened, whereupon the air will pass directly downward on to the paste and will continue to circulate with- 20 out a great deal of mixture of the fresh air.

In drying paste of the character described, it is necessary that the fresh paste shall be subjected to relatively warm and moist currents of air so that it will not be dried too 25 quickly. This may be readily accomplished with my machine, by permitting the air once drawn through the drying chamber 10 to pass again and again through the drying chamber. Then after the paste is dried a 30 sufficient amount, so that it will not crack, the air passage 23 may be closed up by shutting the door or valve 24 and the air drawn entirely through the louver 21 so as to subject the paste to currents of relatively cool 35 dry air which will dry the paste more quickly. It will be seen that the rapidity with which the air passes through the paste and the rapidity with which the fresh air is drawn through the chamber will depend 40 upon the extent with which the window 18 is opened and that even the passage of air through the trunk 23 may be regulated by regulating the extent to which the doors 24 and 25 are opened. Ordinarily, these doors 45 24 and 25 will be either closed or opened. Under many circumstances, it is not desirable to have a very great volume of air drawn longitudinally through the chamber 10 as this may tend to blow about the strings of 50 alimentary paste so that they will become crumpled or twisted and adhere to each other. This is avoided by allowing the air to pass downward through the openings 26. The air may be allowed to pass downward 55 through these openings 26 and also through the full length of the passage 23 and in through the louver 22. It is also obvious that means may be provided in connection with the louver 21 for regulating the amount 60 of fresh air which may be drawn in. I have shown for this purpose a series of shutters 28 which may be readily adjusted to reduce the area of the openings through which fresh air passes. It is to be understood, of course, 65 that the capacity of the chamber 10 may be

greatly increased over what has been illustrated, depending entirely upon the capacity of the plant.

For the purpose of warming the fresh air prior to its entrance into the circulating 70 chamber 20, I provide the steam pipes 29 which may be in the form of a radiator or any other suitable appliance which will uniformly heat the air, these steam pipes being shown as extending vertically upward 75 through the chamber 20. On days where the fresh air is damp and cold, the dampers 28 are closed or nearly closed and in that case the air is allowed to circulate continuously through the drying chamber, the air passage 80 23 and back into the drying chamber, the air being warmed by the steam pipes. Any fresh air which may be allowed to enter is also warmed and to a certain extent dried by the steam pipes. Where the air is too 85 dry, as at the beginning of the drying operation, when too quick drying is to be prevented, the shutters or dampers 28 may be closed and the air is continuously circulated through the drying chamber and the circulating chambers, the air being slightly dampened by contact with the drying paste and being warmed by contact with the warm paste. After the paste has been initially 90 dried, however, in the manner above described, it is possible to further and quickly dry by cutting off the entrance to the air passage 23 and allowing fresh air to pass entirely through the drying chamber. This 95 fresh air may be warmed or not, as desired, by means of the radiators 29 or other heat appliances of any suitable construction, radiators however, being preferred. It is obvious that where cool air is desired the radiators can be shut off. 100

While I have referred throughout the specification to the fact that this machine is particularly used for drying alimentary pastes, it is to be understood that the machine is also adapted to be used for drying 110 tobacco, cigars, fruits, vegetables and other articles of a similar nature.

Having described my invention, what I claim is:—

1. A drying apparatus including a drying chamber open at opposite ends, a circulating chamber at each end of the drying chamber, an air passage connecting the circulating chamber and having a plurality of openings leading into the drying chamber, means at one end of the drying chamber for moving air therethrough, means for admitting fresh air to the circulating chamber located at the opposite end of the drying chamber from said air moving means, means for controlling the passage of air through any one of said openings from the air passage into the drying chamber, and means for preventing the inlet of air into either or both ends of the air passage from either circulating chamber. 130

2. A drying apparatus including a drying chamber open at opposite ends, a circulating chamber at each end of the drying chamber, an air passage connecting the circulating chamber, means for causing air to flow through the chamber in one direction, means for closing one or both ends of the air passage to prevent the passage of air therethrough, means for permitting air from the 5 air passage to enter the drying chamber directly at a plurality of points, and means for mixing fresh air with the air already used prior to the entrance of this air into the drying chamber.
- 10 3. A drying apparatus comprising a drying chamber open at opposite ends and having charging doors and side walls, circulating chambers, one at each end of the drying chamber, a suction fan at one end of the 15 drying chamber discharging into the adjacent circulating chamber, a passage connecting the circulating chambers, a louver at the end of the drying chamber opposite the fan, and a louver in the wall of the adjacent 20 circulating chamber, and means for permitting or preventing the passage of air along 25 said air passage.
4. A drying apparatus including a drying chamber open at opposite ends, air circulating chambers at opposite ends of the drying 30 chamber, one of said circulating chambers being provided with a controllable outlet, means drawing air through the drying chamber and discharging it into the last 35 named circulating chamber, controllable means for admitting fresh air into the opposite circulating chamber, a louver admitting air from said last named circulating chamber into the end of the drying chamber 40 opposite the air drying means, an air passage connecting the circulating chambers, and a door in said passage, in one position permitting the circulation of air therethrough and in the other position preventing 45 said circulation.
5. A drying apparatus including a drying chamber open at opposite ends, circulating chambers disposed one at each end of the drying chamber, a suction fan at one end 50 of the drying chamber and discharging into the circulating chamber at the other end of
- the drying chamber, the other circulating chamber having means for admitting fresh air thereto, a louver in the adjacent end of the drying chamber, an air passage connecting the circulating chambers and extending over the top of the drying chamber, controllable doors at opposite ends of the air passage, said air passage having openings extending into the drying chamber and 55 disposed at spaced intervals, and means for controlling the passage of air downward 60 through said openings.
6. A drying apparatus comprising a drying chamber having doors at its sides, the 65 drying chamber being open at its ends, trucks movable into the drying chamber and having paste drying racks, circulating chambers disposed one at each end of the drying chamber, a suction fan drawing air 70 through the drying chamber and discharging it into the adjacent circulating chamber, a controllable air discharge from the last named circulating chamber, a louver admitting air to the other circulating chamber, 75 a louver disposed in the end wall of the drying chamber opposite the fan, an air passage connecting the circulating chambers and extending over the top of the drying chamber, and means for preventing or 80 permitting the passage of air through the air passage.
7. A paste drying apparatus including a drying chamber open at opposite ends, means for causing air to flow through the 85 chamber in one direction, means for directing the air so drawn through the chamber back to the entrance thereof or preventing such return of the air, means for permitting the air drawn through the chamber 90 to be directed into the drying chamber at a plurality of points, means for mixing fresh air with the air already used prior to its entrance into the chamber, and means for heating the fresh air prior to its entrance 95 into the drying chamber.

In testimony whereof I hereunto affix my signature in the presence of two witnesses.

AUGUST TEGOLI.
